Leather Weight Lifting Belt, [site visited Aug. 24, 2021]. Available from Internet. URL: <https://www.amazon.co.uk/RAD-Leather-Lifting-PowerLifting-Support/dp/B0762LB9BQ> (Year: 2021).*

Primary Examiner — T Chase Nelson

Assistant Examiner — Kelly L Gross

(57) **CLAIM**

The ornamental design for a weightlifting belt, as shown and described.

DESCRIPTION

FIG. 1 is a perspective view of a weightlifting belt showing my new design;

FIG. 2 is a front elevation view thereof, shown enlarged in scale;

FIG. 3 is a rear elevation view thereof, shown enlarged in scale;

FIG. 4 is a left side elevation view thereof;

FIG. 5 is a right side elevation view thereof;

FIG. 6 is a top plan view thereof; and,

FIG. 7 is a bottom plan view thereof.

The broken lines depict stitching lines which form part of the claimed design.

1 Claim, 7 Drawing Sheets
